CLAIM

The ornamental design for a cutting guide as shown and described.

DESCRIPTION

FIG. 1 is a front, top perspective view of a cutting guide comprising the new design;

FIG. 2 is a back, bottom perspective view of the design of FIG. 1;

FIG. 3 is a front elevational view of the design of FIG. 1;

FIG. 4 is a back elevational view of the design of FIG. 1;

FIG. 5 is a right elevational view of the design of FIG. 1;

FIG. 6 is a left elevational view of the design of FIG. 1;

FIG. 7 is a top view of the design of FIG. 1; and,

FIG. 8 is a bottom view of the design of FIG. 1.

The regular dash-dash lines are included for the purpose of illustrating portions of the cutting guide that form no part of the claimed design.

1 Claim, 5 Drawing Sheets
